UNITED STATES PATENT OFFICE

120,374

DESIGN FOR A COMBINED CAN CARRIER AND DISPLAY RACK

Arthur Brandes, Arcadia, Ralph A. Quirk, Los Angeles, and Ralph J. Burke, Beverly Hills, Calif.

Application February 14, 1939, Serial No. 82,972

Term of patent 7 years

To all whom it may concern:

Be it known that we, Arthur Brandes, Ralph A. Quirk, and Ralph J. Burke, citizens of the United States and residents of Arcadia, Los Angeles, and Beverly Hills, respectively, in the county of Los Angeles, State of California, have invented a new, original, and ornamental Design for a Combined Can Carrier and Display Rack, of which the following is a specification, reference being had to the drawing, forming part thereof.

The figure is a perspective view of a combined can carrier and display rack, showing our new design.

We claim:

The ornamental design for a combined can carrier and display rack, substantially as shown.

ARTHUR BRANDES.
RALPH A. QUIRK.
RALPH J. BURKE.
